AIR CLEANER

John C. Enblom, St. Paul, Minn., assignor, by direct and mesne assignments, of twenty-five per cent to Ruth C. Donaldson, twenty per cent to Robert H. Donaldson, twelve and one-half per cent to A. Donaldson Olin, six and one-fourth per cent to Mae D. Buckeye, six and one-fourth per cent to Ralph A. Buckeye, and twenty-five per cent to Ruth C. Donaldson as trustee, and five per cent to Margaret M. Donaldson

Application March 22, 1939, Serial No. 263,487

6 Claims. (Cl. 183—15)

My invention relates to air cleaners and is in the nature of an improvement on or modification of air cleaners of the type disclosed and claimed in the Lowther Patents No. 2,130,142 of date September 13, 1938, and No. 2,006,927 of date July 2, 1935. The particular object of the present invention is to provide an air cleaner in which there will be a more complete and intimate commingling of air and oil in the air cleaning action; and these objects I accomplish by the improved arrangement illustrated in the accompanying drawings and hereinafter more fully described.

Referring to the drawings:

Fig. 1 is a view chiefly in vertical section but with some parts in full and some parts broken away illustrating my invention as applied to an air cleaner of the type illustrated in the said Lowther Patent No. 2,130,142; and

Fig. 2 is a view chiefly in vertical section but with some parts in full illustrating my invention as applied to an air cleaner of the type disclosed in the said Lowther Patent No. 2,006,927.

My invention may, however, be applied to and incorporated with air cleaners other than the types above referred to as the Lowther air cleaners.

Referring first to the structure illustrated in Fig. 1, numeral 5 indicates an upright, cylindrical or drum-like casing, preferably of sheet metal, the top of which is closed by a head 6 having a clean air outlet pipe 7. At its lower portion the casing 5 is surrounded by a skirt 8 spaced therefrom but rigidly attached thereto at its upper edge. The skirt 8, as shown, is provided with a plurality of air intake ports 9. Telescoped on to the skirt 8 is a large cup-like oil well 10 which is detachably held in place by suitable means such as nut-equipped bolts 11 that depend from lugs 12 on the exterior of said skirt and work through the ends of a clamping bar 13 extended under the bottom of the oil well.

Formed on or otherwise placed within the oil well 10 is an oil cup 14 that is of considerably less diameter than the casing 5. The vertical annular flange of the cup 14, for an important reason presently to be noted, is outwardly and upwardly flared or projected at 15 to form one side of an annular deflecting baffle, the other side of which deflecting baffle is formed by an annular flange 16 that is secured to or formed as a part of the lower edge of the casing 5.

Preferably, and as shown, the flange 16 is formed by an upturned portion of a downward

extension of the casing 5. The spaced edges of the flanges 15 and 16 form a continuous or substantially continuous annular combined air and oil passage 17 that is at the level or substantially 10 at the normal static level of the oil Y contained in the well 10 and cup 14. The annular passage 17 is constricted in respect to the air intake passage 8' and is concentric thereto. The interior of the casing 5 forms an expansion chamber 18 above the passage 17 and, of course, this expansion chamber has very much greater cross-sectional area and, hence, conducting capacity, than either the air intake passage 8' or the said passage 17. Preferably and as shown, wire screens or elements 19 are placed in the said expansion chamber.

In the operation of the cleaner just described, the clean air outlet pipe 7 will usually be connected to the carburetor intake of an internal combustion engine so that air, under action of suction, will be drawn in through the perforations 9 of the skirt 8 and down into the oil from the lower end of the annular air passage 8' and from thence will be drawn upward into the expansion chamber 18 through the contracted or constricted passage 17. Because of the smaller conducting capacity of the passage 17, the air with the oil taken up therewith, will move through the said passage 17 under relative very high velocity. As the oil laden air passes through the constricted passage 17 into the expansion chamber 18, a rapid expansion and rapid decrease in velocity will take place which will permit the oil particles in the air to be condensed on the stacked screens, if the latter are provided, from which screens the collected oil will tend to flow under the action of gravity back in the direction of the oil well. However, even if the screens should not be provided the rapid expansion and reduction of velocity will cause a precipitation of the oil particles.

Since the air stream expands rapidly as it enters the expansion chamber 18, the most active zone in the expansion chamber 18 will be 45 directly above the constricted passage 17, and the velocity will fall off progressively as the air stream diverges inwardly and outwardly from opposite sides of the passage 17 so that there will be a relatively quiet zone directly over the oil cup 14, and another relatively quiet zone directly over the flange 16. Under operation of the air in the expansion chamber, the oil particles condensed upon the screen elements or otherwise precipitated from the rapidly moving air stream will flow downwardly in the relatively quiet zones

above noted and will tend to build up a head of oil directly above the oil cup 14, as indicated by dotted lines y' and another head of oil of annular form directly above the flange 16 as indicated by dotted lines y'' . These heads of oil will be the result of displacement of oil under prolonged operation from that annular portion of the oil well outward of the oil cup 14, and which may hereinafter be referred to as the primary oil container. These heads of oil y' and y'' will, of course, tend to return to that portion of the oil well referred to as the primary oil container through the constricted passage 17, but under high capacity operating conditions this return will be largely eliminated and the oil 10 tending to overflow the edges of the passage 17 will be whipped up by the expanding air stream and commingle therewith, only to be precipitated therefrom in the manner already described within the intermediate portion of the expansion 20 chamber and returned back to the vicinity of the passage 17.

As previously indicated, when the air cleaner is acting at high capacity the oil will be largely displaced from the primary oil container, but the loss of this oil from the primary oil container will be offset by the resultant oil heads y' and y'' , which latter constantly tend to flow back into the primary oil container, but do, as a matter of fact, simply feed the expanding air stream 30 with a continuous supply of oil. In this connection it will be understood that there will be a very great turbulence of air at opposite edges of the air stream as it expands over the edges of the passage 17, and this turbulent air will 35 whip up such oil as tends to flow into the passage 17 and cause the same to be thoroughly commingled with the air, which will result in the efficient coating of dust particles with oil and the resultant retaining of the same in the oil 40 body. Of course, when the engine is stopped, the oil will settle back to a static condition as indicated in the drawings.

It is important here to note the important action that takes place as the oil-laden air moves upward through the passage 17. The oil-laden air delivered to the passage 17 from the outward flange 15 will be upwardly projected with a force tending to form the same into an upwardly diverging or expanding cone; while the oil-laden air delivered to the passage 17 by the flange 16 will be projected upwardly with a force tending to form an upwardly converging conical formation. However, these suggested cones will not be formed as indicated but the two streams 55 or sprays will be thrown into violent conflict, at high velocity, which will set up a turbulence resulting in spreading, breaking up and forming of eddies so that the whole violently agitated oil spray will be thoroughly commingled.

In counter-distinction to the above described action, due to the manner in which the oil-laden air is delivered to the constricted passage, it may be stated that if the same volume of oil and air were to be delivered through a cylindrical 65 passage of any considerable length, the oil and air would be projected in the form of a diverging spray having less divergence and turbulence than is produced by the arrangement described and which, as demonstrated in practice, would not have the high degree of efficiency of the arrangement above described.

The annular flanges 15 and 16 converge toward the restricted passage 17 and form a baffle between the expansion chamber and the primary 75

oil container, which latter, in the present instance, is the oil well 18. The flange 15 has the above noted tendency to project the spray on lines marked a ; while the flange 16 has the tendency to project the spray on lines marked b .

Referring now to the construction illustrated in Fig. 2, the numeral 20 indicates an upright cylindrical or drum-like casing, preferably of sheet metal, the top of which is closed by a head 21 through which an air intake tube 22 is extended axially downward through the casing 20. The casing is provided at its upper portion with a clean air outlet tube 23. Telescoped on to the lower end of the casing is a large cup-like oil well 24 which is detachably held in place by suitable means, which means such as nut-equipped bolts 25 depend from lugs 26 on the exterior of the casing 20 and work through the ends of a sustaining bar 27 extended under the bottom of the oil well. Within the oil well 24, by means of a flange or otherwise, there is formed an oil cup 28 that is of much less diameter than the oil well 24. The air intake tube 22 extends downward into the oil cup 28 and to a point considerably below the normal static level of the oil Y' contained in said oil well.

The upper edge of the rim of the cup 28 is contracted and inwardly turned at 29 to form a deflecting flange. A co-operating outwardly and upwardly projecting annular deflecting flange 30 is secured on the lower end of the air intake tube 22 and is spaced from the edge of the inturned flange 29 to form an annular contracted combined oil and air passage 31. This passage 31 is preferably continuous and in any event should be substantially continuous.

The numeral 32 indicates intercepting screens, preferably of wire, that fill the space of the expansion chamber 33 formed between the air intake tube 22 and the casing.

The operation of the form of the air cleaner shown in Fig. 2 is very similar to that described in connection with the form shown in Fig. 1. In the structure of Fig. 1 the air is drawn inward 45 and downward through the annular air intake channel, thence through the oil and thence upward through the casing; while in the structure illustrated in Fig. 2, the air is drawn axially downward, thence through the oil and thence upward through the annular expansion chamber 50 formed within the casing. In the structure of Fig. 2 the contracted or restricted air and oil passage 31 has much less conducting capacity than either the air intake tube or the expansion chamber of the casing, so that the oil and air will be drawn through this contracted passage at relatively very high velocity and the velocity of the oil and air will be decreased in the expansion chamber so that there will be proper precipitation of the oil while the clean air will move upward through the clean air discharge tube or passage. Also, in the structure of Fig. 2 the inturned flange 29 of the oil cup will tend to deflect the oil spray upward in a contracting 60 conical formation while the flange 30 will tend to project the oil spray upward in an outwardly flaring conical formation. Also, the tendency to form these conflicting conical projections of the oil spray results in breaking up the true conical formations and set up eddies and whirling actions much the same as that described in the structure of Fig. 1. Also, the contracted passage 31 is located at or substantially at the normal oil level.

When the air cleaner of Fig. 2 is in action at

relatively high capacity, the oil will be largely displaced from the inner oil cup 28, which may hereinafter be referred to as the primary oil container, with the result that inner and outer heads of oil, indicated by dotted lines y^2 and y^3 respectively, will be maintained and which will constantly tend to flow back into the oil cup through the constricted passage 31. Of course in this instance as in the case of the cleaner of Fig. 1, these heads of oil, due to the high velocity of air moving through the passage 31 under operating conditions, will not actually flow downwardly through the constricted passage 31 under high capacity operating conditions but will simply flow into the expanding air stream. Here also, as in the case of the cleaner of Fig. 1, the oil flowing back to the edges of the rapidly expanding air stream will be whipped up and mingled with the expanding air only to be separated therefrom within the expansion chamber so that a constant circulation of oil within the expansion chamber will be maintained.

In the structure illustrated in Fig. 2 the flanges 29 and 30 converge toward the restricted passage 31 and form a baffle between the expansion chamber and the primary oil container, which latter, in the present instance, is the so-called oil cup 28. The flange 30 has the tendency to project the spray on lines marked a' ; while the flange 29 has the tendency to project the spray on lines marked b' .

In the specification and the claims the primary oil container is the part through which the dust-laden air is primarily delivered and hence, in Fig. 1 the outer annular portion of the part specifically called the oil well 10 is the primary oil container; while in the structure shown in Fig. 2, the part specifically called the oil cup 28 is the primary oil container.

What I claim is:

1. In an air cleaner, a casing having an air inlet and an outlet and annular wall providing an expansion chamber between said inlet and outlet, a second annular wall surrounding the lower portion of said casing wall and providing said air inlet passage and said outlet leading directly outwardly from the upper portion of said casing, an oil well detachably connected to said second annular wall with said casing wall extending into said well below the static oil level, an oil cup mounted within said oil well inwardly of said casing wall and below said expansion chamber, and an annular baffle extending from said casing wall to said cup between said oil well and said expansion chamber, and said baffle having opposed upwardly converging flanges spaced to form a constricted air and oil discharge passage from said oil well to said expansion chamber.

2. The structure defined in claim 1 in which the top of said baffle and said constricted annular passage is approximately at the normal static oil level of said oil well and oil cup.

3. In an air cleaner, a casing having an air

inlet and an air outlet and an annular wall between said inlet and outlet providing an expansion chamber, said inlet being of tubular form extended axially downward through said casing 5 and said outlet leading from the upper portion of said casing, an oil well detachably connected to the lower end of said casing, an oil cup within said well located below and receiving the lower end of said tubular air intake, and an annular baffle extending outwardly from said tube to said oil cup below said expansion chamber and provided at its top with opposed upwardly converging substantially annular flanges spaced to form a constricted substantially annular passage leading from said oil cup to said expansion chamber, said air intake, expansion chamber, oil well and oil cup being in concentric arrangement.

4. The structure defined in claim 3 in which the top of said baffle and said constricted annular passage is approximately at the normal static oil level of said oil well and oil cup.

5. In an air cleaner, a casing having an air inlet, an outlet and an expansion chamber between said inlet and outlet, an oil well in the base of said casing having an upwardly opening oil cup mounted therein and providing primary and secondary oil containers for said cleaner, said expansion chamber having an annular wall radially spaced from the wall of said cup and extending into one of said oil containers below the static oil level thereof and under which inlet air is adapted to pass to said expansion chamber, an annular baffle extending from said chamber wall to the upper edge of said cup below said expansion chamber, and said baffle having spaced upwardly converging flanges providing therebetween a constricted oil and air passageway at approximately the static oil level in said containers and discharging outwardly into said expansion chamber.

6. In an air cleaner, a casing having generally concentric walls providing primary and secondary oil containers in the base thereof and an expansion chamber above said containers, an outlet communicating with the upper end of said expansion chamber, one of said walls extending from said expansion chamber into one of said containers below the static oil level thereof and providing an air inlet to said casing, an annular baffle extending from said one wall to an adjacent concentric wall between said container and said expansion chamber, and said baffle having opposed upwardly converging inner and outer annular flanges spaced to form a constricted oil and air inlet passageway communicating with said expansion chamber at approximately the static oil level in said containers, whereby said inner flange will produce an outward projection of oil and air and the outer flange an inward projection of oil and air from said passageway into said expansion chamber toward the outlet thereof.

JOHN C. ENBLOM.
